US00D811351S

(12) **United States Design Patent** (10) **Patent No.:** **US D811,351 S**
(45) **Date of Patent:** **** Feb. 27, 2018**

(54) **REMOTE CONTROL**

(71) Applicant: **HUNTER FAN COMPANY**,
Memphis, TN (US)

(72) Inventor: **Patrick O'Connell**, Germantown, TN
(US)

(73) Assignee: **Hunter Fan Company**, Memphis, TN
(US)

(**) Term: **15 Years**

(21) Appl. No.: **29/582,072**

(22) Filed: **Oct. 25, 2016**

(51) **LOC (11) Cl. 14-03**

(52) **U.S. Cl.**

USPC **D13/168**

(58) **Field of Classification Search**

(74) *Attorney, Agent, or Firm* — McGarry Bair PC

(57) **CLAIM**

The ornamental design for a remote control, as shown and described.

DESCRIPTION

FIG. 1 is a top perspective view of a remote control;
FIG. 2 is a bottom perspective view of the remote control of FIG. 1;
FIG. 3 is a top view of the remote control of FIG. 1;
FIG. 4 is a bottom view of the remote control of FIG. 1;
FIG. 5 is a front side view of the remote control of FIG. 1;
FIG. 6 is a rear side view of the remote control of FIG. 1;
FIG. 7 is a right side view of the remote control of FIG. 1; and,
FIG. 8 is a left side view of the remote control of FIG. 1. Portions of the remote control shown in broken lines form no part of the claimed design.

1 Claim, 8 Drawing Sheets
